ATTORNEY

UNITED STATES PATENT OFFICE

HORACE S. MELDAHL, OF NEW YORK, N. Y.

WALL RADIATOR

Application filed June 7, 1930. Serial No. 459,728.

This invention relates to a wall radiator, the general object of the invention being to provide a device of this nature which can be manufactured to sell at low cost and one which can be easily and quickly placed in position under a window or in an opening in any other desired location.

Another object of the invention is to provide a valve, preferably operated by the foot of a person for controlling the flow of the heating fluid through the radiator to regulate the temperature of the room or place in which the radiator is arranged, this valve being so arranged that in one position thereof, all the fluid will pass through the radiator, in another position, none of the fluid will pass through the radiator and in intermediate positions, but part of the fluid will flow through the radiator.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

Figure 1 is a front view of the invention, with parts broken away.

Figure 2 is a section on line 2—2 of Figure 1.

Figure 3 is a section on line 3—3 of Figure 1.

Figure 4 is a section on line 4—4 of Figure 3.

In this drawing, the numeral 1 indicates a casing having its front open and which is adapted to be placed on or in an opening in a wall of a room or other place to be heated, preferably under a window. A grill plate 2 covers the open front of the casing, this plate resting against the flanges 3 formed at the top and bottom of the casing and having flanges at its ends which are fastened to the ends of the casing.

Coils A and B are arranged in parallel relation in the casing, said coils being verti-

cally arranged and are each preferably formed of elongated loops 4, each loop being wider at one end than at the other, with the limbs of the loop converging. The wide end of one loop is placed uppermost and the wide end of the next loop lowermost so that the loops are alternately arranged and the narrow end of a loop of one set of coils is arranged opposite the wide end of a loop of the other set, as shown in Figure 1, so that the coils provide the maximum amount of radiating surface in the minimum amount of space and with all parts of the tubing out of contact with other parts so that the air to be heated will come in contact with the entire exterior surfaces of the coils. A pair of rods 5 is placed between the two sets of coils and small wires 6 are passed around portions of the coil and the rods and around another pair of rods 7 placed in rear of the coil B and then the wires are passed through holes in rear of the casing and twisted as shown at 8 to hold the parts in position. Thus it will be seen that the rods 7 space the coil B from the casing and the rods 5 space the two sets of coils from each other.

A valve casing 9 is placed in a lower corner of the casing 1 and a supply pipe 10 is connected with this casing. The coil B is connected with the casing at the point 11 and coil A is connected with the casing at the point 12. A by-pass pipe 13 is connected with the valve casing at the point 14 and this pipe passes horizontally through the bottom of the casing 1. It will, of course, be understood that the coils A and B are connected together at that end of the casing 1 which is opposite the end in which the valve is located so that the heating fluid will pass from the valve casing through one set of coils and then return to the valve casing through the other set. It will also be understood that the two sets of coils may be formed from a continuous length of tubing, as shown in the drawing, and may be wound in other shapes.

A valve 15 is arranged in the valve casing and a double pedal 16 is connected with the valve stem and is located in front of the grille plate so that it may be actuated by the foot of a person. As shown in Figure 4, when

the valve has been moved to a vertical position, the heating fluid will pass from the pipe 10 through the valve casing into coil B and after passing through coil B in one direction, it will enter coil A and pass through the same in an opposite direction and thus return to the valve casing and from said casing the fluid will flow through the pipe 13. Thus all the fluid is passing through the radiator. 10 When the valve 15 is moved to a horizontal position, none of the fluid will enter the coils, but will all pass through the pipe 13. In intermediate positions of the valve, some of the fluid will enter the radiator and the rest will flow directly into the pipe 13. Thus the flow of fluid is controlled by the valve and said valve provides means for regulating the temperature of the room in which the device is placed. This valve also provides means 15 for facilitating the draining of the system by siphon means or the like.

A small electric motor M is arranged in the lower part of the casing 1, at the center thereof, and a fan 17 is fastened to the shaft 25 of the motor and is located in front of the grill plate 2, with a cage 18 enclosing the fan. Thus this fan will increase the circulation of air into and from the device, but its use is optional. Portions of the coils may 30 be bent to accommodate the motor, as shown in Figures 1 and 2.

From the foregoing it will be seen that I have provided a radiator which can be constructed to sell at low cost and one which 35 can be placed in an opening in a wall under a window or in any other place in or on a wall and the flow of the heating fluid thereof is controlled by a single valve which may be operated by the foot of a person.

40 It is thought from the foregoing description that the advantages and novel features of the invention will be readily apparent.

It is to be understood that changes may be made in the construction and in the combination

45 and arrangement of the several parts, provided that such changes fall within the scope of the appended claims.

What I claim is:—

1. A radiator of the class described comprising a number of coils each formed of elongated loops having their ends connected together, a valve casing to which the front ends of the coils are connected, a supply pipe connected with the casing, a discharge pipe connected with the casing and a valve member in the casing for causing the fluid from the supply pipe to flow through the coils or through the discharge pipe without entering the coils or through both the coils and the discharge pipe.

2. A radiator of the class described comprising a casing adapted to be placed on a wall or in an opening in a wall or the like and having its front open, a pair of coils in 65 the casing arranged in parallel position and

with their rear ends connected together, a valve casing in the casing to which the front ends of the coils are connected, a discharge pipe connected with the valve casing, a supply pipe connected with the valve casing, a valve member in the valve casing for causing the fluid from the supply pipe to pass through the coils and then through the discharge pipe or through the discharge pipe without entering the coils or through both the coils and the discharge pipe.

3. A radiator of the class described comprising a casing adapted to be placed in an opening in a wall or the like and having its front open, a pair of coils in the casing arranged in parallel position and with their rear ends connected together, a valve casing in the casing to which the front ends of the coils are connected, a discharge pipe connected with the valve casing, a supply pipe connected with the valve casing, a valve member in the valve casing for causing the fluid from the supply pipe to pass through the coils and then through the discharge pipe or through the discharge pipe without entering the coils or through both the coils and the discharge pipe, a grille plate closing the front of the casing and means whereby the valve member can be operated by the foot of a person.

4. A radiator of the class described comprising a casing, spaced parallel vertically arranged coils therein, a supply pipe for supplying heating fluid to the coils, a discharge pipe, valve means for causing the fluid to pass through the coil and then the discharge pipe or through the discharge pipe without entering the coil or through both the coil and the discharge pipe, and means disposed at one end of the casing and protruding beyond the facing of the casing, whereby the valve member can be mechanically operated.

5. A radiator of the class described comprising a series of alternately arranged coils having their ends connected together, means for spacing the coils from one another, a valve casing to which the front ends of the coils are connected, a supply pipe connected with the casing, a discharge pipe connected with the casing, and a valve member in the casing causing the fluid from the supply pipe to flow through the coils or through the discharge pipe without entering the coils or through both the coils and the discharge pipe.

In testimony whereof I affix my signature,
HORACE S. MELDAHL.
